UNITED STATES PATENT OFFICE

107,343

DESIGN FOR A LAMP

Victor Nemeroff, Chicago, Ill., assignor to Electro Manufacturing Co., Chicago, Ill., a corporation
of Illinois

Application October 2, 1937, Serial No. 71,927

Term of patent 7 years

To all whom it may concern:

Be it known that I, Victor Nemeroff, a citizen of the United States, residing at Chicago, in the county of Cook and State of Illinois, have invented a new, original, and ornamental Design for a Lamp, of which the following is a specification, reference being had to the accompanying drawing forming part thereof.

Fig. 1 is a front plan view of a lamp embodying
my new design; the dotted portion of the globe

represents colored glass, and the rectangular portion left open is to represent frosted glass;

Fig. 2 is an end view thereof; and

Fig. 3 is a bottom plan view of the same, showing the colored and frosted glass as referred to with reference to Fig. 1.

I claim:

The ornamental design for a lamp as shown
and described.

VICTOR NEMEROFF.
